UNITED STATES PATENT OFFICE.

CHARLES MANSHEL, OF PROVIDENCE, RHODE ISLAND.

VENDING-MACHINE.

959,063.

Specification of Letters Patent. — Patented May 24, 1910.

Application filed January 2, 1908. Serial No. 470,379.

To all whom it may concern:

Be it known that I, CHARLES MANSHEL, a citizen of the United States, residing at Providence, in the county of Providence and 5 State of Rhode Island, have invented certain new and useful Improvements in Vending-Machines, of which the following is a specification.

My invention relates to coin feed machines 10 for vending and printing tickets, stamps and similar articles from a strip located in a casing whence they are delivered through an aperture to the purchaser.

The essential purposes of my invention are 15 to facilitate the charging and operating of structures of this character; to prevent the delivery of more than one ticket at one discharge, and render pilfering of the tickets or coin difficult or impossible; to give visual 20 and aural alarms when the supply of tickets or stamps is nearly exhausted; to facilitate the detection of spurious coins; and to render the operation of the printing and stamp delivery mechanism certain, accurate and positive.

With the above objects in view and others, as will appear as the description proceeds, the invention comprises the various novel 30 features of construction and arrangement of parts and combinations of parts hereinafter described and set forth in the appended claims.

It will be understood that various changes in form, proportions, size and minor details 35 of structure may be made without departing from the spirit or sacrificing any of the advantages of the invention.

I shall hereinafter by way of illustration describe a ticket vending machine in connection with the accompanying drawings which form a part of this specification, and in which like reference characters indicate like parts throughout the views.

Figures 1 and 2 are front and side elevations respectively of my machine. Fig. 3, a side elevation of the upper portion of the same with part of the casing removed, Fig. 4, a front elevation of the operating mechanism with the front of the casing omitted, 50 Fig. 5, a section on line *w w* of Fig. 4, Fig. 6, an enlarged detail view of a marginal portion of the large feed roll or drum and co-operating pawls, Fig. 7, a partial section on *x x* of Fig. 6, Fig. 8, a plan of the mechanism 55 with the top of the casing removed, and part

of the mechanism broken away, Figs. 9 and 10, sections on lines *y y* and *z z* respectively of Fig. 8, and Fig. 11, a front view of the machine, the front of the case being broken away.

In the present embodiment of my invention, 1 is a hollow case of metal or wood mounted upon a hollow standard, 2, from which it is separated by a floor, 3, provided with an opening, 4. The case, 1, is divided into upper and lower compartments, 5 and 6, by a horizontal partition, 7, slidably supported by guides, 8, fixed to or integral with the case walls. The front wall of the case comprises a fixed portion, 9, and a door or removable panel, 10, secured by lock, 11, or otherwise. The former has a display opening, 12. In the door is a horizontal ticket slot, 13, and a rectangular opening, 14, but the opening is not essential. The upper portion of the door has an indicator opening, 15, provided with a transparent glass, 16, bearing the word "Empty."

A convenient form of coin controlled operating mechanism for use in conjunction with the delivery mechanism is the following: Upon the front of slide, 7, is fixed a box or housing comprising front, rear, and side walls, 18, 19, 20 and 21. The wall, 18, abuts the opening, 14, and constitutes a portion of the front wall of the case. It is provided with a coin slot, 22, and interspaced stops, 23 and 24, upon its outer face. Mounted in walls, 18 and 19, is a rock shaft, 25, upon whose outer end is fixed an operating handle or crank, 26, and carrying two segmental plates, 27, 27, connected by an inclined coin plate, 28, provided with a longitudinal slot, 29, in its lower portion. The top surface of the plate, 28, is in the plane of the coin slot, 22; and to guide the inserted coin is a plate, 30, fixed to the upper end of plate, 28. Upon the lower end of the latter plate are coin retaining ears, 31. Loose upon shaft, 25, between the segmental plates is a sleeve, 32, provided with a forwardly projecting locking finger, 33, for supporting a coin, and which extends through the slot, 29, of the coin plate. A second arm, 34, upon the sleeve has its end 105 fixed in a curved cam plate, 35, provided with a laterally curved cam edge, 36, terminating in a stop shoulder, 37. The plate, 35, is normally downwardly pulled by a helical spring, 38, whose ends are connected 110

to the cam plate and to a pin, 39, in the wall, 18. Also fixed to the wall, 18, is a coin clearer, 40, whose end, 41, is in alinement with the coin plate slot, 29. Upon one of the segmental plates, 27, is a dog, 43, in which is a pin, 44. The coin plate, 28, is rearwardly pulled by a spiral spring, 45, having one end fast to the pin, 44, and its other end, to a pin, 46, in a horizontal guide plate, 47, forwardly extending and integral with the rear wall 19. A similarly disposed guide plate, 48, is located at the opposite end of the wall. These two guide plates are respectively interspaced from walls, 20, and 21, as at 50 and 51, respectively. Pivoted at 52 to the rear wall, 19, is an arm, 53, having an outwardly curved or cam face, 54, upon its upper end, and an intermediate shoulder, 55, adapted to swing into the path 20 of a finger, 56, fixed to the rear portion of shaft, 25. The arm, 53, is drawn into the path of the finger by a spring, 58, fixed at one end to the arm, and at its other end to a pin, 59, in the wall, 19. Mounted in the 25 lower portion of the walls, 20, 21, is a rock shaft, 61, to which are fixed two vertical flat plates, 62 and 63. The latter plate, as shown in Fig. 8, has a cut away portion, 64, in its rear edge to facilitate movement of the 30 arm, 53. A lug, 65, upon the inner face of plate, 63, is adapted to contact with the cam surface of plate, 35. The oscillatory plates are rearwardly tensioned by a spring, 66, attached at one end to pin, 67, in plate, 63, 35 and at its other end to a pin, 68, in the rear wall. The oscillatory or vibratory plates are connected at their tops to form a yoke. This yoke in this instance comprises a cross piece, 69, to which is fixed by screws, 70, a reinforcing piece or block, 71. Stop lugs, 73, are located upon the front of piece, 69. Integral with the yoke or fixed thereto in any convenient manner is a projection or pin, 76, adapted to engage mechanism hereinafter described.

The operation of the coin mechanism is as follows: A coin inserted in the coin slot falls by gravity along the plate, 28, and rests upon the end of finger, 33, where it is held until the manual rotation of the shaft, 25, through lever, 26, brings the coin plate into a position to permit the coin clearer, 41, to dislodge the coin which drops into a funnel, 78, in the slide, 7, and thence into a cylindrical glass tube, 79. During the described movement of the shaft, 25, the coin holds the cam plate, 35, in fixed relation to the shaft and the edge 36, of the cam plate in its descent forwardly forces the plates 62, 63, and their cross piece, 71, and finger, 76, which sets into operation the vending mechanism. During the forward movement of the parts as described the shoulder, 55, of the arm, 53, is drawn beneath the path of the finger, 56, so that the handle lever, 26,

of the shaft, 25, after a partial turn, cannot be returned again to upright position until the arm, 53, is forced back by the return of the plate, 63, to its original position. The transparent coin magazine or tube, 79, may be attached to the funnel, 78. The former is mounted in a socket, 80, fixed to the front wall, 9, of the case. Pivotedally mounted intermediate its length upon a bracket arm, 81, fixed to the wall, 9, is a lever, 82, provided at its forward end with a disk, 83, adapted to normally press against the open lower end of the receptacle, 79, and having upon its opposite end a counterweight, 84. After a predetermined number of coins enter the tube, 79, their weight is sufficient to overcome the weight of member, 84, and thus automatically force the disk, 83, away from the tube and permit the accumulated coins to fall into a receptacle in the chamber, 6, 85 or through the floor opening, 4, into the casing standard whence they may be removed through a panel or door, 86, in the case standard. In order to detect spurious coins, the tube, 79, is illuminated by an electric lamp, 87, mounted upon a bracket arm, 88, fixed to the case, and connected with any convenient external source of electrical supply through a conductor, 89, passing through an opening, 90, in the casing wall.

The ticket delivering mechanism comprises the following parts: An upright or standard, 92, has its base, 93, fixed by screws, 94, or otherwise to the slide, 7. Pivotedally mounted upon a stud or shaft, 96, is a feed drum, 97, provided upon its periphery with an annular strip, 98, of soft material or fabric, and upon each side of this strip with an annular row of round protuberances, 99, interspaced to correspond with marginal notches, 100, located at the divisional points of the tickets in the strip, 101, to be delivered from the periphery of the drum. Fixed to or integral with one face of the drum, 97, is a gear, 103. Loosely mounted at one end upon the stud, 96, is an arm, 105, provided with an oblong slot, 106, into which extends loosely the pin, 76. This arm is also provided midway its length with lateral finger, 107, elevated somewhat from the plane of the arm.

The means for intermittently advancing the drum is the following: Pivoted upon a pin, 108, upon the outer end of arm, 105, is a lever, pawl, or hook, 109, provided with an upwardly curved end, 110, and a marginal recess, 111, and adapted to engage consecutively individuals of an annular row of pins, 113, near the margin of the drum face interspaced to correspond with the length of a ticket. The means for supporting the hook, 109, consists, as shown in Fig. 7, of a pin, 114, slidably mounted in a recess, 115, in the hook provided with a conical head, 116, adapted to register in a cavity, 117, in the 130

arm, 105, and pressed into the cavity by a spring, 118, in the recess abutting against the pin head. A tripping pin, 120, for the hook is fixed in the wall, 20, and projects 5 to a point near the periphery of the drum, 97, in the path of the hook. A depression of the operating handle, 26, while the coin mechanism is locked, advances through the pin, 76, the arm, 105, and the hook, 109, 10 which is in engagement with a pin, 113, the drum 97, the distance of a ticket. At the close of this advance the hook is lifted out 15 of engagement with its pin by the contact of the end of the hook with the pin, 120, as shown in Fig. 6. The release of the coin, and the simultaneous action of spring, 66, returns the arm, 105, after each advance to its original position shown in Fig. 5. During this return the elevated end, 111, 20 of hook, 109, strikes one of a circular series of pins, 122, upon a type drum, 123, hereinafter described, which throws the hook down into engagement with the next succeeding pin, 113, and its pin, 114, into its 25 seat, 117. The position of the hook at the instant of contact with the pin, 122, is shown in broken lines in Fig. 6. Each intermittent advance of the drum moves the strip the distance of a ticket through the 30 slot, 13, to which it is guided by a plate, 124, fixed to the standard. The strip is held against the drum face near the ticket slot by a presser or friction roll, 127, upon a pin, 128, in the standard, which roll also 35 operates with the protuberances, 99, to prevent the displacement of the strip while a ticket is being manually detached by upward pressure of the strip against the edge of a blade, 129, fixed in the front wall of the case. 40 To prevent overrotation of the drum or surreptitious movement of the same to secure a plurality of tickets at one coin insertion, the following mechanism is employed. Fixed to the rear of the standard, 93, is a 45 stud, 131, to which is pivoted a depending detent, 132, whose thickened free end, 133, is in the plane of the pins, 113, and of the finger, 107, which is normally in contact therewith. The upper end of the detent has 50 a stop shoulder, 134, adapted to engage a stop pin, 135, upon the stud, 131. A spring, 136, fixed to the stud presses against the outer edge of the detent. When the machine is idle the finger, 107, normally holds 55 the detent out of the path of the pins, 113, and permits the advance of the feed drum, as shown in Fig. 5. During the delivery of a ticket, however, as shown in Fig. 6, the spring, 136, forces the detent in the path of 60 the pins and limits further advance of the drum.

A mechanism co-operates with the feed drum, 97, for dating the tickets successively as they are fed. This comprises the printing drum, 123, rotatably mounted upon a

stud, 139, in the upright, 93, above the drum, 97, provided with a plurality of peripheral slots, 140, in which are seated a row of type, 141, frictionally retained by clamping screws, 143, in the outer face of the drum, 70 123. The inner ends of the rows of type are in frictional contact with a ratchet disk, 144, also mounted upon the stud, 139. Adjacent this disk loose upon stud, 139, is a gear, 145, meshing with gear, 103. Both 75 the members, 144 and 145, are connected with the drum, 123, by screws, 146, but they may be integral therewith. As the drum, 123, is rotated by the gear, 103, the type contacts with the strip passing over the feeding drum. To prevent reverse movement of the drum, 123, is a pawl, 146', adapted to engage the ratchet disk, 144, pivoted to a pin, 147, in the upright, and downwardly pressed by the end, 148, of a spring, 149, 80 wound on the pin.

The inking device for the type drum comprises a pin, 151, retained in the upright, 93, by a thumb screw, 153, or otherwise, and upon whose end is rotatably mounted an 90 ink roll, 154, adapted to contact with the type as the drum, 123, rotates.

The ticket strip, 101, is supplied to the feed drum from a reel, 156, whose hub, 157, is loose upon a stud, 158, on a depending 95 bracket, 159, fixed by screws, 160, to the bottom of slide, 7. The strip passes through an opening, 162, in the slide, 7, and over a guide roll, 163, mounted on 1 stud, 165, in the upright below the drum, 97; and 100 passes thence to the surface of the drum to whose lower rear surface it is pressed by a roll, 166, on a stud, 167, in the standard. Pivoted to a pin, 168, in the bracket, 159, above the roll is an arm, 169, to whose lower 105 face is fixed a copper plate, 170, between which and the arm is insulating material, 171. Upon this plate is a binding post, 172. The plate normally rests by gravity upon the periphery of the roll, 173, of tickets 110 upon the hub, 157, serving as a drag upon the roll and preventing the coils of the roll from springing away from each other. When, however, the last layer or coil of tickets leaves the hub, the plate, 170, contacts 115 with the hub, 157, to complete an electrical circuit energized by a battery, 174, upon the base, 7, and including an indicator light, 175, in the case behind the glass, 16, and an alarm bell, 177, also fixed to the case interior. 120 A switch, 178, for breaking the circuit, is located on the base, 7, or on a lug, 179, upon the base. The described location of the battery, light, bell, or switch is not exclusive. In fact, the bell might be located in a place 125 remote from the machine. In this instance, the circuit, which is shown diagrammatically, comprises a wire, 180, leading from the battery to the switch, a wire, 181, from the switch to the pin or post, 168. From post, 130

A mechanism co-operates with the feed drum, 97, for dating the tickets successively as they are fed. This comprises the printing drum, 123, rotatably mounted upon a

172, is a wire, 182, leading to the lamp, 175, thence a wire, 183, leads to the battery, 174, completing the lamp circuit. The bell circuit includes a wire, 184, connecting the post, 172, and bell, 177, and wires, 185 and 174, leading from the bell to the battery. By virtue of the insulation, 171, the current passes from the post, 168, through the bracket, 159, stud, 158, and hub, 157, which are all of metal, so that until the roll, 173, is exhausted, the circuit is broken. When the contact plate, 170, touches the hub, 157, the current traverses the plate, 170, and the post, 172, thereon, whereby the public and attendant are notified, through the display, 16, and bell, 177, that the supply of tickets in the machine is nearly exhausted.

The location of substantially all the operative parts upon a slidable base, 7, not only makes the structure a unit, but permits their ready removal from the case through the door, 10, whereby the parts may be repaired or the ticket roll replenished.

What I claim is,

25. 1. In a machine of the type set forth, the combination with a rotary feeding drum, of a supporting shaft on which it is mounted, vibrating means loosely supported on said shaft for rotating the drum, radial means on the support of said vibrating means, and a pivoted member coöperating with said drum and the radial means for locking the drum against over-rotation.

30. 2. In a machine of the type set forth, the combination with a rotary feeding drum, of a shaft therefor, an arm loosely mounted on said shaft, means on and movable with said arm for rotating the drum, radial means on said arm, a pivoted member coöperating with the drum and the radial means for locking the drum against over-rotation, and means for giving the arm an intermittent motion for moving the strip the distance of a ticket at each intermittent advance of the drum.

35. 3. In a machine of the type set forth, the combination with a rotary feeding drum, of a shaft therefor, vibrating means loosely mounted on said shaft for rotating the drum, radial means on said vibrating means, a pivoted member coöperating with said drum and the radial means for locking the drum against over-rotation, and means actuated by the feeding drum for printing tickets.

40. 4. In a machine of the type set forth, the combination with an intermittently rotating feeding drum, of a vibratory member operatively connected with said drum and adapted to propel the same, a hand-operated shaft, an arm loosely mounted upon the axis of the drum and having a lateral finger, and pivotally mounted means having its free end in the plane of said finger.

45. 5. In a machine of the type set forth, the combination with an intermittently rotating

feeding drum, of a vibratory member operatively connected with said drum and adapted to propel the same, a hand-operated shaft, an arm loosely mounted upon the axis of the drum and having a lateral finger, and pivotally mounted means having its free end in the plane of said finger and normally contacting therewith.

6. In a machine of the type set forth, the combination with an intermittently rotating feeding drum, of a vibratory member operatively connected with said drum and adapted to propel the same, and a hand-operated shaft, a cam loose upon the shaft engaging the vibratory member, spring means for swinging said member in one direction, means for swinging the member in the opposite direction, and coöperating means for locking said cam and shaft and means coöperating with the rotating means for preventing overrotation of the drum.

7. In a machine of the type set forth, the combination with a rotary feeding drum, its shaft, an arm loosely mounted on said shaft, a vibrating member pivoted on said arm to intermittently rotate the drum, pivoted means coöperating with the drum and means on said arm for locking the drum against over-rotation, and a revolute type drum adjacent the feeding drum and adapted to co- operate therewith.

8. In a machine of the type set forth, the combination with a rotating feed drum, of means for rotating it, a lateral arm on said rotating means, vibratory mechanism coöperating with the lateral arm of said rotating means and with independent means on the drum, for preventing overrotation of the drum, and means for operating said over-rotation-preventing mechanism.

9. In a machine of the type set forth, the combination with a feeding drum adapted to advance a strip of tickets, of means for pressing the strip against the periphery of the drum, vibrating means pivoted on the shaft of the drum for intermittently rotating the drum, means upon the periphery of the drum for locking the strip against movement relatively to the drum, means actuated by the drum for printing the tickets of the strip, and means embodying a vibratory member for actuating the drum and means coöperating with the feeding drum for locking it against over-rotation.

10. In a machine of the type set forth, the combination with a rotary feeding drum, of a revolving type drum adjacent the feeding drum and adapted to coöperate therewith, mechanism actuating the feed drum, means coöperating with the feeding drum for locking it against over-rotation and a pawl and ratchet device for preventing a reverse movement of the type drum.

11. In a machine of the type set forth, the combination with a base of a standard on

the base, two studs upon the standard, a feeding drum rotatably mounted upon the first stud a driving gear loose upon the same stud, a type drum revolvably mounted upon 5 the second stud, a driven gear loose upon the second stud and fixed to the type drum, pins upon the standard, friction rolls upon the pin in contact with the periphery of the feeding drum, marginal pins upon the face 10 of the feeding drum, an arm pivotally mounted at one end to the first stud and provided with a longitudinal slot, a hook pivotally mounted upon the outer end of the arm in the path of the pins, a vibratory yoke 15 pivotally mounted upon the base adjacent the arm, a pin upon the yoke registering in the slot of the arm, and means for vibrating the arm.

12. In a machine of the type set forth the 20 combination with a base, of a standard upon the base, a stud upon the standard, a feeding drum loose upon the stud, a circular row of pins upon the face of the drum, an arm loosely mounted upon the stud and provided 25 with a slot, a hook upon the arm in the path of the pins, a lateral finger upon the arm, a pin upon the standard, a detent upon the pin extending into the path of the pins adjacent the end of the finger, a vibratory 30 yoke pivotally mounted upon the base adjacent the arm, a pin upon the yoke registering in the slot of the arm, and means for vibrating the arm.

13. In a machine of the type set forth, the 35 combination with a rotary feeding drum, means adapted to rotate the same, a printing drum, and an ink roll, of operative connections between said drums, means for actuating the feeding drum, means coöperating 40 with said drum for preventing its over-rotation, and a pawl and ratchet mechanism for preventing the reverse rotation of the printing drum.

14. In a machine of the type set forth the 45 combination with a rotary feeding drum adapted to receive a ticket strip upon its periphery, and mechanism adapted to rotate the same, of a delivery reel adapted to support the rolled portion of the strip, a roll 50 intermediate the reel and drum for tensioning the strip, and an arm held by gravity against the rolled portion of the strip and an alarm operatively connected with the hub on which the delivery reel is supported 55 for coöperation with said arm when the strip is exhausted.

15. In a machine of the type set forth, the 60 combination with a rotary drum for advancing a ticket strip, and mechanism embodying a vibratory member coöperating with said drum for actuating the latter, of a reel for supporting the rolled portion of the strip being delivered to the drum, a signal light, and means electrically connected with the signal light and normally bear-

ing upon said strip and actuated by the reel for indicating the absence of the strip from the reel.

16. In a machine of the type set forth, the combination with a rotary drum for advancing a ticket strip, and mechanism embodying a vibratory member coöperating with said drum for actuating the latter, of a reel for supporting the rolled portion of the strip being delivered to the drum, an 70 alarm bell, and means electrically connected with the bell and normally bearing upon said strip and actuated by the reel for indicating the absence of the strip from the reel.

17. In a machine of the type set forth, the combination with the case provided with a ticket slot, of a blade fixed to the case at the margin of the slot, a rotary drum within the case adapted to intermittently advance a ticket strip through the slot the distance 85 of a ticket, lateral means on the drum, means within the case embodying a vibrating member connected with the shaft of the drum, and a lateral pin loosely movable in a slot therein, and means coöperating with 90 the drum-rotating means and with lateral means on the drum for preventing over-rotation of said drum.

18. In a machine of the type set forth, the combination with an intermittently rotating 95 feed drum, of means for intermittently rotating the feed drum comprising an arm loosely mounted upon the axis of the drum and having a lateral finger, and an oblong slot, a lateral pin loosely movable in said 100 slot, lateral pins on said drum, and a pivotally mounted depending detent with its free end in the plane of said pins and said finger and normally in contact therewith.

19. In a machine of the type set forth, the 105 combination with an intermittently rotating feed drum, of means for intermittently rotating the feed drum comprising an arm loosely mounted upon the axis of the drum and having a lateral finger, and an oblong 110 slot, a lateral pin loosely movable in said slot, lateral pins on said drum, a pivotally mounted depending detent with its free end in the plane of said pins and said finger and normally in contact therewith, and a 115 spring acting on said detent.

20. In a machine of the type set forth, the combination with an intermittently rotating feed drum, of means for intermittently rotating the feed drum comprising an arm 120 loosely mounted upon the axis of the drum and having a lateral finger, and an oblong slot, a lateral pin loosely movable in said slot, lateral pins on said drum, a pivotally mounted depending detent with its free end 125 in the plane of said pins and said finger and normally in contact therewith, a spring acting on said detent, the upper end of said detent being provided with a stop shoulder, and a relatively fixed coöperating stop. 130

21. In a machine of the type set forth, the combination with an intermittently rotating feed drum, of means for intermittently rotating the feed drum comprising an arm loosely mounted upon the axis of the drum and having a lateral finger, and an oblong slot, lateral pins on said drum, a pivotally mounted depending detent with its free end in the plane of said pins and said finger and normally in contact therewith, and means coöperating with said slot to intermittently rotate the drum.
22. In a machine of the type set forth, the combination with an intermittently rotating feed drum, of means for intermittently rotating the feed drum comprising an arm loosely mounted upon the axis of the drum and having a lateral finger, and an oblong slot, lateral pins on said drum, a pivotally mounted depending detent with its free end in the plane of said pins and said finger and normally in contact therewith, means coöperating with said slot to intermittently rotate the drum, and means for automatically disengaging the rotating means.
23. In a machine of the type set forth, an intermittently rotating feeding drum, of means for intermittently rotating the feed drum comprising an arm mounted on the axis of said drum and having a slot, means coöperating with said slot, a hook pivoted on said arm, and engaging lateral projec-

tions on the drum, a type drum, and lateral projections thereon for coöperation with said hook, whereby the latter intermittently rotates the type drum.

24. In a machine of the type set forth, the combination with a rotary feeding drum adapted to receive a ticket strip upon its periphery, and mechanism adapted to rotate the same, of a delivery reel adapted to support the rolled portion of the strip, an arm resting against the rolled portion of the strip, and an alarm operatively connected with the hub on which the delivery reel is supported for coöperation with said arm when the strip is exhausted.

25. In a machine of the type set forth, the combination with a rotary drum for advancing a ticket strip, and means for actuating said drum, of a reel for supporting the rolled portion of the strip being delivered to the drum, a signal light, and means electrically connected with the signal light and normally bearing upon said strip to contact with the hub of the reel when the strip is completely unwound for indicating the absence of the strip from the reel.

In testimony whereof I have affixed my signature in presence of two witnesses.

CHARLES MANSHEL.
